TUBULAR STRIPPING SHOE OR THE LIKE

Henriette Simon, Croton on Hudson, N. Y.

Application October 26, 1951, Serial No. 17,134

Term of patent 7 years

(Cl. D7—7)

To all whom it may concern:

Be it known that I, Henriette Simon, a citizen of the United States of America, residing in Croton on Hudson, county of Westchester, and State of New York, have invented a new, original, and ornamental Design for a Tubular Stripping Shoe or the like, of which the following is a specification, reference being had to the accompanying drawing, forming part thereof.

Fig. 1 is a perspective view of a tubular stripping shoe, showing my new design.

Fig. 2 is a cross section taken at the vamp portion of Fig. 1 at line 2—2.

The rear is substantially the same appearance as that shown.

I claim:

The ornamental design for a tubular stripping shoe or the like, substantially as shown and described.

HENRIETTE SIMON.
